(57) **CLAIM**

The ornamental design of a handset, as shown and described.

DESCRIPTION

FIG. 1 is a bottom plan view of a handset showing our new design; and

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof;

FIG. 8 is a perspective rear view thereof;

FIG. 9 is a front view of the handset of FIGS. 1-8 in an open in-use position;

FIG. 10 is a perspective front view of the handset of FIGS. 1-8 in an open in-use position;

FIG. 11 is a right side view of the handset of FIGS. 1-8 in an open in-use position;

FIG. 12 is a left side view of the handset of FIGS. 1-8 in an open in-use position;

FIG. 13 is a rear view of the handset of FIGS. 1-8 in an open in-use position;

FIG. 14 is a bottom plan view of the handset of FIGS. 1-8 in an open in-use position; and,

FIG. 15 is a top plan view of the handset of FIGS. 1-8 in an open in-use position.
